UNITED STATES PATENT OFFICE.

PETER E. KROEHLER AND WERNER PETTERSON, SR., OF NAPERVILLE, ILLINOIS, ASSIGNEES, BY MESNE ASSIGNMENTS, TO S. KARPEN & BROS., OF CHICAGO, ILLINOIS, A CORPORATION OF WEST VIRGINIA.

SOFA-BED.

987,998.

Specification of Letters Patent. Patented Mar. 28, 1911.

Application filed April 8, 1909. Serial No. 488,695.

To all whom it may concern:

Be it known that we, PETER E. KROEHLER and WERNER PETTERSON, Sr., citizens of the United States, residing at Naperville, in the county of Dupage and State of Illinois, have invented certain new and useful Improvements in Sofa-Beds, of which the following is a specification.

This invention is an improvement in sofa-beds, and relates more especially to a combination davenport and bed.

The primary object of the invention is the production of a device of this character of such construction that when arranged to form a sofa or davenport there will be nothing in its appearance to indicate that it is convertible into a bed, and when arranged in the form of a bed a wide mattress is brought into position and firmly supported for use, while the upholstered seat of the davenport is turned down and located under the front part of the mattress so as to be protected during the use of the device as a bed.

With this principal object in view the invention consists in the particular construction and arrangement of parts constituting the combination davenport and bed, all as hereinafter fully described and specifically set forth in the appended claims.

In the accompanying drawings, which form a part of this specification: Figure 1 is a front elevation, the device being arranged in the form of a sofa or davenport. Fig. 2 is an end view, the near side of the davenport being removed to disclose the parts by which the device is convertible into a bed. Fig. 3 is a similar view, with the upholstered seat of the davenport raised to show the operation of the several parts. Fig. 4 is a similar view, with the parts arranged in bed form.

Like numerals of reference indicate like parts in all the figures of the drawings.

In carrying out the invention we employ in the first place all the principal parts common to the usual form of davenport; that is to say, a frame consisting of the end pieces 5 and back 6, an upholstered seat 7, and a front rail 8, the end pieces having front posts 9, and said end pieces and the back connected by corner-posts 10, as is usual. In the present instance the seat and front rail, together with other parts hereinafter

described, are movable within the frame for the purpose of converting the davenport into a bed, and the several parts constituting the davenport may be of any suitable ornamental design or finish.

The front rail 8 is pivoted at its ends, near its upper edge, between the front posts 9 of the frame of the davenport, such pivotal connection being formed preferably by means of short bars or metal straps 11, secured to the ends of the rail and having headed pivot-pins 12 which engage in key-hole slots 13 formed in attaching-plates 14 secured to the inner side of said front posts. The short bars or metal straps 11 are extended beyond the pivot for connection with the upholstered seat 7 at one corner thereof, this connection being by means of a pivot 15, so as to permit said upholstered seat to be swung into and out of the frame, for the purpose hereinafter mentioned. Hingedly connected to the other end of each short bar or metal strap 11 or directly to the front rail 8, is a bar 16, which is pivotally connected at its rear end to the upper end of a lever 17, the latter being pivoted at its lower end to a corner-post 10 of the frame. The pivotal connection between the lever 17 and bar 16 is by means of a bracket-plate 18, secured to the bar, so as to locate the pivot-point a slight distance above the bar for the proper action of a lifting spring 19, which is connected at one end to the bar in front of said pivot-point and at its other end to the post 10 in the rear of and slightly above the horizontal plane of the lower pivot-end of the lever. Hooked plates 20 and 21 are provided for connecting the spring to the bar and post, respectively.

Connected to the upholstered seat 7, and to the movable bar 16 is a mattress frame comprising the opposite end sections 22 and 23, and a short center section 24, the end section 22 being connected by a link 25 to the bar 16, the center section connected to a standard 26 rising from one corner of the seat 7, and the other end section 23 connected by a link 27 to the other corner of said seat, whereby the several mattress frame sections are suitably supported by said bar and seat and are adapted to move therewith. The sections or frames 22, 23 and 24 are provided with suitable mattresses, and in the present instance the several sections are

covered by a single piece mattress, so as to provide an unbroken surface when the device is arranged in bed form, as shown in Fig. 4.

5 For the purpose of supporting the outer ends of the mattress and seat, when the parts are arranged in bed form, we provide a supporting leg 28 at each end of the seat, said legs being pivoted near their upper ends to 10 said seat, and connected each by a rod 29 to the metal straps at the ends of the front rail 8, the connection of these parts being such that when the seat is swung outward the leg will assume a vertical position, to 15 form the support, and when the seat is swung into the frame the said leg will assume substantially a horizontal position so as to lie across the end of the seat below the upper edge thereof. For operating the pivoted seat a strap or loop 30 is attached to 20 the inner edge thereof, as shown in Fig. 3.

As will be seen by reference to the drawings, the connections between the mattress sections and coöperating parts are such that 25 when the seat 7 is in the position within the frame to form a sofa or davenport (Figs. 1 and 2), said mattress sections will be folded below the seat, with the sections 22 and 23 lying horizontally one above the other, and 30 the center section 24 disposed vertically directly in the rear of the front rail 8, whereby said mattress, as well as the mechanical devices for operating and supporting the same, are entirely concealed, and the device 35 thus forms a davenport with nothing to indicate that it is convertible into a bed.

When it is desired to arrange the device into bed form the seat is swung upward and forward by grasping the strap or loop 30, 40 and when it is lowered to position in front of the frame will be supported at its outer end by means of the leg 28 and at its inner end by means of the connection with the front rail 8. As will be seen this operation 45 is assisted by the lifting spring 19, and during such operation the bar 16 is raised by the rearward movement of the front rail and the connection of said bar with the throwing-lever 17, thus elevating the rear 50 section of the mattress and also the center and front sections, so that they will all be on a horizontal line. In its raised position the mattress frame is firmly supported at its ends and center by means of the supporting 55 links 25 and 27, and standard 26, so that the device may form a substantial bed. When the device is closed in sofa or davenport form there is a space left between the superimposed end sections of the mattress, 60 and this space may be utilized for storing bed clothing during the use of the device as a sofa or davenport. It will be understood, of course, that similar connections between the mattress-frame, seat and sofa 65 frame are located at each end of the device,

as is usual in devices of this character, and we prefer that the lifting-bars 16 be connected at their front and rear ends by means of cross-pieces; and also that the standards 26 which are rigidly secured to the seat be 70 suitably braced. As each lifting-bar 16 is hinged to its companion short bar or strap 11, which latter carries the seat and front-rail, said bars 16 and 11 together form a jointed bar for operating the rear mattress 75 section and supporting leg as the seat is swung into and out of the frame.

Having thus described our invention, what we claim as new and desire to secure by Letters-Patent, is:—

1. In a convertible sofa and bed, the combination with the sofa frame and seat pivoted between the ends thereof, of a mattress frame comprising pivotally connected sections, standards connecting the center 85 section to the pivot-end of the seat, and means for connecting the outer sections to the underside of the seat and to the frame of the sofa respectively.

2. In a convertible sofa and bed, the combination with the sofa frame and seat, the latter being pivoted at its forward ends between the end pieces of the frame, of a mattress frame comprising pivotally connected sections, standards connecting the center 95 section to the pivot-end of the seat, and movable links connecting the outer sections of the mattress frame to the underside of the seat and to the sofa frame respectively.

3. In a convertible sofa and bed, the combination with the sofa frame, of a front rail pivoted between the ends thereof, a seat pivoted to the upper end of the front rail at one side of its pivot, a mattress frame 105 comprising pivotally connected sections, and means for connecting the mattress frame sections to the seat and to the front rail, the latter connection being at the other side of the pivot from the connection of the seat with said rail.

4. In a convertible sofa and bed, the combination with the sofa frame, of a front rail pivoted between the ends thereof, a seat pivoted to the upper end of the front rail at one side of its pivot and adapted to swing into and out of the sofa frame, a mattress frame comprising pivotally connected sections, movable members connecting one of the sections of the mattress frame to the seat, movable members connecting the opposite section to the front rail at the other side of the pivot from the connection of the seat with said rail, and a lifting lever connected to the sofa frame and to one of the 110 movable members last mentioned.

5. In a convertible sofa and bed, the combination with the sofa frame, of a front rail pivoted between the ends of the frame, a seat pivoted to the upper end of the front 115 120 125 130

5 rail at one side of its pivot and adapted to swing into and out of the sofa frame, a mattress frame comprising pivotally connected sections, standards connecting the center section to the pivot end of the seat, movable members connecting the sections of the mattress frame to the seat and to the front rail, the latter connection being at the other side of the pivot from the connection of the seat

10 to said front rail, a lifting lever connected to the sofa frame and to one of said movable members, and a lifting spring connected to the sofa frame and to a movable member.

15 6. In a convertible sofa and bed, the combination with the sofa frame, of a seat pivotally supported between the ends of the sofa frame so as to swing into and out of said frame, a mattress comprising pivotally connected sections, movable members connecting the sections of the mattress frame to the seat and to the sofa frame, a lifting lever connected to one of the movable members, and a lifting spring also connected to one of the movable members.

20 7. In a convertible sofa and bed, the combination with the sofa frame, of a seat pivotally supported between the ends of the sofa frame so as to swing into and out of said frame, a mattress comprising pivotally connected sections, movable members connecting the sections of the mattress frame to the seat and to the sofa frame respectively, and a lifting lever extending from the sofa frame to one of the movable members; together with legs pivoted to the seat, and rods connecting said legs to one of the aforesaid movable members, substantially as shown and described.

25 8. In a convertible sofa and bed, the combination with the sofa frame, of a seat pivotally supported between the ends of the sofa frame so as to swing into and out of said frame, a mattress frame comprising pivotally connected sections, means for connecting one end of the mattress frame to the seat, a jointed lifting-bar pivotally connected to the sofa frame and to the seat, a lever connecting the free end of the lifting-bar to the sofa frame, and means for connecting a section of the mattress frame to said lifting-bar.

30 9. In a convertible sofa and bed, the combination with the sofa frame, of a seat pivoted at one end between the ends of the sofa frame so as to swing into and out of said frame, a mattress frame comprising pivotally connected sections, links connecting the mattress frame to the seat, a jointed lifting-bar pivotally connected to the sofa frame and to the seat, a link connecting the lifting-bar to a section of the mattress frame, and a lifting lever connected to the lifting-bar and to the sofa frame.

35 10. In a convertible sofa and bed, the combination with the sofa frame, of a seat piv-

totally supported between the forward ends of the sofa frame so as to swing into and out of said frame, a mattress frame comprising pivotally connected sections, links connecting sections of the mattress frame to the seat, a jointed lifting-bar pivotally connected to the sofa frame and to the seat, a link connecting the lifting-bar to a section of the mattress frame, a lifting lever connected to the lifting-bar and to the sofa frame, and a lifting-spring connected to the sofa frame and to said lifting-bar.

40 11. In a convertible sofa and bed, the combination with the sofa frame, of a seat pivotally supported between the forward ends of the sofa frame so as to swing into and out of said frame, a mattress frame comprising pivotally connected sections, means for connecting sections of the mattress frame to the seat, a jointed lifting-bar pivotally connected to the sofa frame and to the seat, means connecting said lifting-bar to one of the sections of the mattress frame, and a lifting-lever connected to the sofa frame and to the lifting-bar; together with a leg pivoted to the seat, and a rod connecting the leg to the lifting-bar, substantially as shown and described.

45 12. In a convertible sofa and bed, the combination with the sofa frame, of a front rail pivoted between the forward ends of the sofa frame, a seat pivoted to the upper end of the front rail and adapted to move the lower end thereof rearward as the seat is swung out of said frame, a mattress frame comprising pivotally connected sections, means for connecting sections of the mattress frame to the seat, a lifting-bar connected to the lower end of the front rail and to one of the sections of the mattress frame, and a lifting lever connected to the sofa frame and to the lifting-bar, substantially as shown and described.

50 13. In a convertible sofa and bed, the combination with the sofa frame, of a front rail pivoted between the forward ends of the sofa frame, a seat pivoted to the upper end of the front rail and adapted to move the lower end thereof rearward as the seat is swung out of said frame, a mattress frame comprising pivotally connected sections, means for connecting sections of the mattress frame to the seat, a lifting-bar connected to the lower end of the front rail and to one of the sections of the mattress frame, and a lifting lever connected to the sofa frame and to the lifting-bar; together with a leg pivoted to the seat, and a rod connecting the leg to the lifting-bar, substantially as shown and for the purpose set forth.

55 14. A sofa-bed comprising a main frame, a seat hinged at its front side to the frame, a folding bed-frame of three sections connected by links to the main frame, a standard rigidly connected to the seat and pivot-

ally connected to the bed-frame, and a spring connected to the main frame and operative to assist in raising the bed-frame when the seat is being turned to a reversed 5 position in front of said main frame.

15. In a structure of the character set forth, the combination of a frame, a forwardly swinging seat adapted to occupy an inverted position in front of said frame, 10 supports depending from said seat near its pivots, an intermediate bed section pivotally connected with said supports, front and rear bed sections pivotally connected with said intermediate bed section, supporting means 15 for the free edge of the front bed section connecting said front bed section with said seat, and supporting means for the rear edge of the rear bed section connecting said rear bed section with said frame.

20 16. In a sofa-bed, the combination of a

frame comprising end standards and a back fixedly mounted thereon, a seat invertibly connected with said frame, a folded bed normally housed in said frame beneath said seat and comprising an intermediate section foldably mounted on said seat and front and rear sections foldably related to said intermediate section, and mechanism operative to automatically unfold the bed sections and elevate the front and rear edges respectively 25 of the front and rear bed sections in the operation of inverting the seat.

In testimony whereof we have signed our names to this specification in the presence of two subscribing witnesses.
